UNITED STATES PATENT OFFICE.

JULIUS E. CURTIS, OF TACOMA, WASHINGTON.

DESIGN FOR A BADGE.

No. 40,171.

Specification for Design.

Patented July 27, 1909.

Application filed May 24, 1909. Serial No. 498,118. Term of patent 3½ years.

To all whom it may concern:

Be it known that I, JULIUS E. CURTIS, a citizen of the United States, residing at Tacoma, in the county of Pierce and State of Washington, have invented a new, original, and ornamental Design for a Badge, of which the following is a specification, reference being had to the accompanying drawing, forming part thereof.

The figure is a plan view of the badge, showing my new design.

I claim:

The ornamental design for a badge, as shown.

JULIUS E. CURTIS.

Witnesses:

M. F. MCNEIL,
FRANK D. BENTLEY.
